TOOLHEAD HANDLE RATCHET WEDGE

Richard B. Breter, Northeast, Pa.

Application April 15, 1947, Serial No. 741,543

4 Claims. (Cl. 306—33)

1

This invention relates to wedge elements for securing tool heads, such as hammer, hatchet, axe, and sledge hammer heads on the ends of handles by wedging surfaces of the handles against adjacent inner surfaces of the heads of the tools, and in particular a wedge element of the usual type in the edges of which spring steel pawls are provided which are positioned to engage with coacting teeth in the corresponding surfaces at the ends of the handle-receiving socket of the tool head.

The purpose of this invention is to provide means in a wedge element for securing tool heads on handles which locks the wedge in the securing position in the head, wherein the wedge cannot work loose.

Wedge elements and devices have been provided of numerous types and designs, with some holding in the wood, or material of the handle, and some locking in the head, but as the wood shrinks or wears, the usual type of wedge works loose and the head finally works off of the end of the handle. With this thought in mind, this invention contemplates a wedge element adapted to be driven into a saw cut in the end of a tool handle in which ratchet elements are incorporated for engaging ridges or teeth in the tool head to positively lock the wedge element in the head with the said wedge element positioned in the saw cut of the handle.

The object of this invention is to provide a wedge having ratchet elements in combination therewith for securing tool heads on handles in which the wedge positively secures the handle in the head.

Another object of the invention is to provide an improved wedge for securing tool heads to handles thereof in which the holding elements thereof are permanently incorporated in the wedge providing a single complete unit.

Another object of the invention is to provide a wedge element for permanently mounting a tool head on a handle in which the wedge is driven into the usual saw cut in the end of the handle.

Another object of the invention is to provide a wedge element for permanently securing tool heads on handles in which play developing in the mounting between the end of the handle and head of the tool may readily be taken up by driving the wedge element further into the handle and head.

A further object of this invention is to provide a wedge element having ratchet elements in combination therewith for positively securing tool

2

heads on handles, which is of a simple and economical construction.

With these and other objects in view, the invention embodies a combination wedge element and tool head wherein the wedge is adapted to be driven into a slit or saw cut in the end of a handle and the edges of the wedge element are provided with extending spring pawls positioned to engage with teeth in the tool head positioned in opposite ends of the handle-receiving socket thereof.

Other features and advantages of the invention will appear from the following description taken in connection with the drawings, wherein:

15 Figure 1 is a view showing a longitudinal section through a tool head, or hammer, with a part of the handle also shown in section and parts broken away, and with the wedge element shown in elevation.

20 Figure 2 is a view showing a side elevation of the wedge element.

Figure 3 is a view showing an end elevation of the wedge element.

Figure 4 is a view showing the hammer or tool head illustrating the position of the ratchet-gripping teeth in the handle-receiving socket thereof.

25 Referring now to the drawings, wherein like reference characters indicate corresponding parts, the improved tool head mounting of this invention includes a wedge element 10, a tool head 11, and a handle 12.

30 The wedge 10 is formed with a large end 13 and sides 14 and 15 thereof sloped from the large end or head to a point 16. The ends 17 and 18 are also slightly tapered, as shown in Figure 2. The edges 17 and 18 are provided with transverse recesses 19 and 20 positioned substantially midway of the length thereof and flat spring steel elements 21 and 22 are positioned in the recesses with the inner ends thereof extending into sockets 23 and 24 of the wedge.

35 The tool head 11 is provided with a handle-receiving socket 25 and the surfaces of the head in opposite ends of the socket are provided with teeth 26 and 27 which are positioned to be engaged by the spring elements 21 and 22 as the wedge 10 is driven into a slit 28 in the end of the handle 12.

40 45 50 55 With the parts arranged in this manner, a tool head may be mounted upon the end of a handle in the usual manner and with the end of the handle provided with a slit 28, the wedge 10 may be driven therein and as the wedge approaches the position illustrated in Figure 1, the spring

elements 21 and 22 will engage the teeth 26 and 27, thereby making it substantially impossible for the wedge element to back up or move outward; and as wear develops in the mounting due to shrinkage of the handle or other elements, the wedge 10 may be driven further in and the spring elements will move along the teeth, thereby positively securing the handle in the head in substantially any position.

The wedge element may be provided in various sizes for hammer, hatchet, axe, and sledge hammer heads, and it will be understood that other modifications may be made in the design and arrangement of the parts without departing from the spirit of the invention.

What is claimed is:

1. In combination, a tool handle having a slit in an end thereof, a tool head having a handle-receiving slot positioned on the end of the handle with the slit therein with the end of the handle extending into the slot in the head and with inner surfaces of the head at opposite ends of the slot provided with transversely disposed teeth, and a wedge element with transverse slots in the edges intermediate the ends and flat springs in said slots extending outward from the ends of the wedge and sloping from the mounting points thereof in the wedge toward the large end of the wedge.

2. A tool head mounting comprising a tool head having a substantially rectangular centrally disposed socket extending therethrough with transversely positioned grooves in the head at opposite ends of the socket, a substantially solid wedge element positioned in said socket, and spring pawls extending outward diagonally from the ends of said wedge element, said pawls inclined from the point of support thereof toward the large end of the wedge.

3. In combination, a tool handle having a slit

in an end thereof, a tool head having a handle-receiving slot positioned on the end of the handle with the slit therein with the end of the handle extending into the slot in the head and with inner surfaces of the head at opposite ends of the slot provided with transversely disposed downwardly-sloping teeth, and a wedge element with transverse slots in the edges intermediate the ends and flat springs in said slots extending outward from the ends of the wedge and sloping from the mounting points thereof in the wedge toward the large end of the wedge.

4. A tool head mounting comprising a tool head having a substantially rectangular centrally disposed socket extending therethrough with transversely positioned downwardly-sloping grooves in the head at opposite ends of the socket, a substantially solid wedge element positioned in said socket, and spring pawls extending outward diagonally from the ends of said wedge element, said pawls inclined from the point of support thereof toward the large end of the wedge.
